METHOD OF PREPARING NATURAL CORK FOR INDUSTRIAL USE.

1,224,264.

Specification of Letters Patent.

Patented May 1, 1917.

Application filed November 7, 1916. Serial No. 130,105.

To all whom it may concern:

Be it known that I, SAMUEL C. BOND, residing at Hollyoak, in the county of New Castle and State of Delaware, a citizen of the United States, have invented or discovered certain new and useful Improvements in Methods of Preparing Natural Cork for Industrial Use, of which improvements the following is a specification.

10 My invention relates to improvements in the preparation of natural cork for industrial use; more particularly, it relates to methods employed in making cork gaskets—particularly those disk-shaped gaskets used in connection with metal bottle-closing caps, to constitute what is known as a "crown cap." The object of my invention is to reduce waste and to improve the quality of the product.

20 This application describes and claims an invention of mine disclosed in my now abandoned application, filed January 12th, 1915, Serial No. 1735.

In making the disk-shaped gaskets for bottle closures mentioned above, the usual practice is to take the natural cork from the bales, which is of all shapes, sizes, and thicknesses, and, after steaming, to slice it into layers. The layers of each piece of cork wood are, after slicing, laid one upon another, as in the original uncut piece, and the whole reassembled piece is brought under a punch, and disks are cut through all the layers with each stroke of the punch.

35 A piece of cork one inch thick is ordinarily cut into about nine layers and so affords nine disks on each stroke of the punch. When the disks have been cut they are sorted; many of them are ready for service as gaskets, but many are imperfect and are not serviceable. The imperfections may consist in small holes running through the disks, and in some grades of cork small hard particles contained in the substance of the

40 material constitute imperfections. Disks which for such reasons are imperfect have heretofore been rejected as unusable; their scrap value is relatively small.

My present invention includes the familiar procedure indicated above, up to the sorting out of the disks, the serviceable from the imperfect. The serviceable disks are used, as heretofore, and the imperfect ones are subjected to further treatment, and re-55 claimed and made serviceable.

I collect the imperfect disks, and first, if necessary, remove from them the hard particles which they may contain. I do this by crushing the hard particles and loosening them or reducing them to powder, so that 60 they will separate from the substance of the cork. To accomplish this, I may pass the disks between rolls, or press them beneath a plunger, or I may (and preferably do) place them in a drum of fine wire mesh and 65 tumble them in such a drum, together with small weights, the weights serving to crush and loosen the hard particles. The screen of which the drum is formed allows the crushed and loosened particles to escape. 70

When the disks have been relieved of these hard particles described, my further method of treatment consists in building them up into a coherent cylindrical rod, and in slicing that rod again into disks. To this end 75 the disks, before being so built up, are coated with a suitable cement. This cement coats the faces of the disks and the holes also. The cement will preferably be of an albuminoid character and susceptible to coagulation: egg or blood albumen, for example, or gelatin in commercial form. The cement may be applied to the disks by tumbling them, together with a proper quantity of it, in a tumbling barrel. When the disks have 80 been coated they may, in the use of certain cements, be built up immediately by superposition into a cylindrical rod, and then either at once or after more or less complete drying the cementing material may be 85 coagulated. If the material be albumen, coagulation will be effected by heat alone. If the cementing material be gelatin, and formaldehyde or another substance having 90 like effect be used as a coagulant, the coagulant may be added to the gelatin before the disks are built up into a rod, or the rod may be built up, and then the coagulant may be 95 applied to it.

The rod is preferably built up in a cylindrical mold of proper size to receive and hold the disks in snug engagement. Heat is applied to the articles within the mold to effect their complete union and (if the cementing material be albumen) to effect coagulation also. The heat expands the air cells within the substance of the cork and the resultant pressure is ordinarily sufficient to effect union. The built-up rod may be forced in continuous length through such 100

105

110

a mold suitably heated, or the mold may be filled, its ends plugged, and then the filled mold may be heated by immersing it in a bath of hot water or steam. If the expansion of the air cells in the substance of the cork is insufficient to effect a satisfactory union of the disks, pressure may be exerted upon the ends of the built-up rod within the cylinder; or, in the case of the heated mold 10 through which the succession of built-up disks is continuously fed, the size of the mold may be such that the pressure required to drive the rod through the mold will be sufficient to effect the desired closeness of 15 union.

The unified and coherent rod when cooled is cut again into disks of proper thickness. The disks cut from the rod will, in almost 20 all cases, be formed of parts of two of the disks of which the rod was initially formed; that is to say, the cuts will seldom correspond with the intercalated films of cement. Consequently, the new disks being formed 25 each of parts of two of the original disks, imperfections which existed in one will usually be overlaid by a perfect portion of 30 the adjacent disk, and the new disk will usually be entirely acceptable as a gasket. As a matter of practice, it may be found desirable to cut the original disks of a thickness other than that of the gaskets ultimately produced; but, if the final cutting be upon planes intermediate the faces of the 35 original disks, the thickness of the disks may be the same in both cuttings, and each of the ultimate disks will be composed of parts of two of the original disks.

The finished disks are sorted, the imperfect ones rejected, and the perfect ones are 40 ready for insertion in the metal caps, to form bottle closures of the familiar crown type.

The accompanying drawings are illustrative of the foregoing description. Figure 45 1 shows in side elevation a rotary tumbling barrel. It is in such a barrel as this that the disks may be tumbled to coat them with cement. Fig. 2 shows in longitudinal medial section a mold in which the built-up

disks may be contained while being compressed and heated and consolidated into an integral cylindrical rod. Fig. 3 shows, in perspective, the rod formed of the original disks cemented together. Fig. 4 shows in plan and Fig. 5 shows in side elevation one 55 of the ultimate disks cut from the rod of Fig. 3.

I claim as my invention:

1. The herein described method of fabricating cork which consists in cutting natural cork to disks, separating the imperfect from the industrially perfect disks, building and uniting with cement the imperfect disks into a coherent rod, and cutting such rod again to disks. 65

2. The herein described method of preparing for industrial use disks of natural cork which consists of building up and uniting with a coagulable cementing material the disks into a coherent rod, coagulating 70 such cementing material, and cutting such rod again to disks.

3. The herein described method of preparing for industrial use disks of natural cork which consists in removing from the 75 disks hard particles contained in them, building up and uniting with cement the so treated disks into a coherent rod, and cutting such rod again to disks.

4. The herein described method of preparing for industrial use disks of natural cork which consists in tumbling the disks in a tumbling barrel, treating them with cementing material, building them into a coherent rod, and cutting the rod again to 85 disks.

5. The herein described method of preparing natural cork for industrial use which consists in slicing the natural cork into layers, subjecting the layers to crushing 90 by strain, removing the material loosened by crushing, and uniting the layers so treated.

In testimony whereof I have hereunto set my hand.

SAMUEL C. BOND.
